UNITED STATES PATENT OFFICE.

SALVATORE SCOGNAMILLO, OF NEW YORK, N. Y.

DESIGN FOR AN AUTOMOBILE-HORN AND MOTOR-CASING.

44,591.

Specification for Design.

Patented Aug. 26, 1913.

Application filed July 16, 1913. Serial No. 779,402. Term of patent 7 years.

To all whom it may concern:

Be it known that I, SALVATORE SCOGNAMILLO, a citizen of the United States, residing at New York, in the county and State of New York, have invented a new, original, and ornamental Design for an Automobile-Horn and Motor-Casing, of which the following is a specification, reference being had to the accompanying drawing, in which the figure is a perspective view of an

automobile horn and motor casing, showing my new design.

I claim:

The ornamental design for an automobile horn and motor casing, as shown.

SALVATORE SCOGNAMILLO.
